UNITED STATES PATENT OFFICE.

WILLIAM E. HARRISON, OF PHILADELPHIA, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed October 18, 1920. Serial No. 417,624.

My invention relates to switch mechanism and particularly to enclosed switches such as are employed in controlling lighting and power circuits.

5 An object of this invention is to provide an interlocking mechanism between the switch mechanism and the cover closing the opening through which the fuse members are accessible, whereby closing movement of 10 the switch is precluded so long as the cover is in open position.

15 A further object is to provide interlocking mechanism between the switch mechanism and the cover whereby opening movement of the cover is precluded so long as the switch member occupies a predetermined open position.

20 Another object is to provide interlocking mechanism between the switch mechanism and the cover whereby opening movement of the cover is precluded so long as the switch is in any position other than its extreme open position, and whereby closing movement of the switch is precluded so long as the cover 25 is in any position other than its closed position.

25 These and other objects that will be made apparent throughout the further description of the invention are attained by means of the 30 apparatus hereinafter described and illustrated in the accompanying drawings, wherein:

35 Figure 1 is a front elevation of a switch mechanism embodying my invention.

40 Fig. 2 is a vertical section on the line II—II of Fig. 1; and

45 Fig. 3 is a transverse section on the line III—III of Fig. 2.

50 Referring to the drawings, the improved interlocking mechanism is shown as applied to a form of switch mechanism illustrated in the co-pending applications for Letters Patent, Serial No. 415,781, filed Oct. 9, 1920, by Henry L. Slausson, and assigned to the 55 Westinghouse Electric & Manufacturing Company. The switch mechanism includes an insulating base 4, upon which are mounted two pairs of stationary switch-jaw members 5 and 6 and two pairs of fuse-clip members 7. Two switch-blade members 8 are pivoted to the jaw members 5 and are adapted to be moved into engagement with the jaw member 6 for closing the circuit through the supply terminals 9, the switch-jaw member 6,

55 the switch-blade member 8, the jaw member 5, the conductor 10, the fuse clip 7, the fuse member 11, the clip 7 and the load terminal 12.

60 A protecting cover or housing 13 encloses the switch member and the fuse members. The cover comprises an arcuate section disposed directly opposite the switch mechanism, the generating center of curvature of the cover being co-incident with the axis of rotation of the switch-blade member. The 65 portion of the housing surrounding the fuse member is somewhat shallower than that enclosing the switch mechanism and is provided with an opening 14 that is closed by a door 15, which is hinged to the housing by 70 means of a hinge-pin 16. This door is normally held closed by means of a tension spring 17 that is secured at one end to the housing as at 18, and at the other end to the 75 door.

75 The door 15 is provided with a sliding latch bar 19 that normally engages a ledge 20 that is turned inwardly from the lower end of the housing to prevent opening movement of the door. The latch-bar 19 is yieldingly retained in latched position by means of an interlocking rocking bar 21 that is pivoted at 22 to clips 23. The clips 23 are secured to that portion 24 of the cover that lies between the arcuate face thereof and the upper end of the opening 14 in the cover. 80

85 One end of the rocking bar is provided with an arcuate portion 25 that projects through a slot 26 provided in the upper end of the latch-bar 19. The opposite end 21 of the rocking bar extends toward the arcuate wall of the cover and is normally held in the position shown, wherein the latch-bar 19 is retained in closed or latched position, by means of a helical compression spring 27 that is disposed between the end of the rocking bar and the wall 24 of the housing. 90

95 The switch blades 8 are connected by means of an insulating bar 28 to which a flat arcuate operating bar 29 is attached. An operating handle 30, having a threaded shank 31, extends in the slot 32 provided in the cover and is screwed into the bar 29. A nut 33, that is non-rotatably secured to the shank 31, serves as a shoulder for limiting inward movement of the handle. The nut is of greater width than the slot 32 and, consequently, the handle may not be removed 100

105

to permit free movement of the cover unless the switch member is moved to an open position wherein the nut 33 registers with the wide section 34 of the slot 32, through which 5 the nut may be withdrawn.

The left edge (Fig. 1) of the bar 29 is provided with a shoulder 35 that engages the end 36 of the rocking bar 21 when the switch is moved to open position. The end 10 36 is depressed thereby and the arcuate section 25 raises the latch-bar 19 and unlatches the door 15. When the switch is moved to closed position, the spring 17 again closes the door.

15 When the switch is in open position, the free end of the operating bar 29 projects through a slot 29', and a perforation 37 therethrough registers with an opening 38 provided in the clip 39 that is secured to the housing wall 24. A padlock 40 may be inserted in the perforations and the switch thereby locked in open position. When the bar 29 is in this position, the shoulder 35 is held just out of engagement with the rocking bar and, consequently, the fuse-compartment door is retained in closed position.

The housing 13 is secured to the panel or base 4 by means of bolts 41 and 42 that are secured to the panel 4 and project through 30 perforate wings 43 and 44, respectively, that are secured to the side walls of the housing. Wing nuts 45 and 46 serve to clamp the housing to the base. It will be observed that the wing nut 46 is disposed within the 35 housing and is accessible only through the opening 14 that is closed by the door 15. The wing nut cannot be removed so long as the door is closed and, therefore, the cover cannot be removed until the switch is moved 40 to an open position wherein the door is unlatched and wherein the handle 30 may be removed.

45 My invention resides in an interlocking device combined with certain elements of the apparatus described above, which consists in a latch bar 47 that is slidably mounted within a guide 48 which is secured to the wall member 24. This bar is provided with an extension 49 (Fig. 3) that is 50 adapted to enter a notch 50 that is provided in the right-hand edge of the arcuate operating bar 29, when the switch member is

moved to an open position wherein the notch 50 is registered with the projection or extension 49. The bar 47 is pivoted to a 55 bracket 51 that is carried upon an extension 52 of the cover 15. When the cover is moved to open position, the projection 49 enters the notch 50 and prevents closing movement of the switch member so long as the cover is in 60 a position other than closed position.

When the switch is moved to open position wherein the perforation 37 registers with the perforation 38 that is provided in the clip 39, the notch 50 is out of registry 65 with the bar 47 and movement of the bar 47 toward the right is prevented by reason of the engagement of the extension 49 with the outer face of the bar 29. The cover or door 15, therefore, is locked in closed position when the switch is locked in open position by means of the padlock 40. The service may, therefore, be interrupted by the service company and the cover closing the fuse compartment locked in closed position 70 through the medium of the interlocking bar just described, while the switch is locked in open position.

75 While I have described and illustrated but one embodiment of my invention, it will be apparent to those skilled in the art that various changes, modifications, substitutions, additions and omissions may be made in the apparatus described without departing from the spirit and scope of the invention, as set 80 forth by the appended claim.

85 I claim as my invention:

The combination with a switch mechanism provided with a housing, a movable switch member within the housing, a movable cover for the said housing, a movable latch for the cover, and an operating member for the switch and the latch provided with a notch, of an interlocking member actuated by the 90 said cover adapted to enter the said notch when the cover is moved to open position to prevent closing movement of the said switch member so long as the cover is in open position.

95 In testimony whereof, I have hereunto 100 subscribed my name this ninth day of October, 1920.

WILLIAM E. HARRISON.
